UNITED STATES PATENT OFFICE.

HERMAN W. STORK, OF BROOKLYN, NEW YORK.

DUMPING-SCOW.

1,319,977.

Specification of Letters Patent.

Patented Oct. 28, 1919.

Application filed August 21, 1919. Serial No. 318,870.

To all whom it may concern:

Be it known that I, HERMAN W. STORK, a citizen of the United States, and a resident of the borough of Brooklyn, county of 5 Kings, city and State of New York, have invented certain new and useful Improvements in Dumping-Scows, of which the following is a specification.

My improvements relate to marine vessels of the scow type used for conveying ashes, garbage, and other refuse to dumping locations, and which are usually towed thereto, going with the tide. The trap or bottom dumping scows now used for the purpose are not reliable because they sometimes fail to open, or the refuse is so closely packed therein that it fails to discharge, in either case necessitating a return tow to port, and another dumping excursion with a succeeding tide. This involves serious loss of time and labor, etc., as well as being otherwise objectionable for various and obvious reasons.

The main purpose of my invention is to obviate these difficulties by automatically 25 and positively dumping the scow load by a reversal thereof substantially as herein-after set forth,—the invention consisting in the specific combination and arrangement of parts described and claimed,—and a distinctive feature being the construction of a duplex scow, with independent twin side pockets or holds pivotally attached to a common keelson plate or partition and provided with air compartments so positioned 35 that when the lower portions of said independent holds are unlocked from the keelson partition the twin holds will automatically reverse themselves, turning upon their pivotal connections with said keelson partition, 40 and thereby positively emptying themselves and dumping their loads effectively and expeditiously. Incidentally my invention includes in conjunction therewith, several mechanical appliances for controlling said twin holds, and returning them to their normal 45 positions as related to the keelson partition after the dumping operation.

In the accompanying drawings,

Figure 1, is a top view of my duplex 50 dumping scow, in normal closed condition;

Fig. 2, is an end elevation thereof partly in section;

Fig. 3, is a transverse vertical section, taken upon plane of line 3—3 Fig. 1, showing 55 the twin holds inverted;

Fig. 4, is a longitudinal sectional elevation

taken upon general plane of line 4—4, Fig. 2, showing the keelson partition broken away in part;

Fig. 5, is a detail view upon a larger scale 60 showing the control mechanism;

Fig. 6, is a view taken upon plane of line 6—6, Fig. 5;

Fig. 7, is a detail view, upon a still larger scale, of the twin hold closure gearing, etc. 65

Fig. 8, is a detail view taken at right angles to Fig. 7, and giving an edge view of the idler pulleys shown in the lower part of said Fig. 7;

Fig. 9, is a sectional detail of the crank 70 shaft ratchet, etc.;

Fig. 10, is a detail view of the transmitting gear sleeve.

What may, for convenience of description, be designated as the keelson partition 75 K, extends vertically the whole length of the scow and constitutes the means of copulation, as well as of division, between the twin holds H, H', the latter being pivotally attached to the upper portion of said keelson partition K, and also when in normal position, detachably fastened to the lower portion thereof. Such connection between the keelson partition K, and the holds H, H', may obviously be effected by various well 80 known mechanical expedients, so that I do not limit myself in this respect to the identical construction of parts shown herein by way of exemplification,—the essential feature being a pivotal attachment of the holds 85 H, H', to the upper portion of the keelson partition in conjunction with means for normally locking the said holds to the lower portion of said partition. As shown in the drawings this is accomplished by means of 90 trunnion bolts t', t², passing through the upper portions of the end walls h, h, of the holds H, H', and secured to bracket plates k, k, on the keelson partition K; and by bolt rods b, b, on the ends of said partition 95 engaging with I brackets h', h', on the lower portions of the holds H, H. These bolt rods b, b, extend through guiding and supporting bearings k', k', on the ends of the partition K, and are actuated by means of links 100 b², b², connected with crank arms b³, b³, on the ends of a rock shaft b⁴, mounted on and between bearings k^x, k^x, on the upper ends of the keelson partition K, said shaft b⁴, being rocked when desired by means of a hand lever b⁵, connected with another crank arm b⁶, on the shaft b⁴, through the medium of

105

110

the link b^7 , and connection rod b^8 — b^9 , being a suspender link pivotally supported at b^{10} , on a bracket k^2 , and pivotally connected with the aforesaid link b^7 , and connection rod b^8 , for the purpose of controlling and rendering effective the stroke of the link b^7 , and rod b^8 , and also to preserve the proper relationship of operative parts when the holds are turned into dumping position. In other words, the effective radius of the link b^9 , is equivalent to the distance between the pivotal center b^{10} , and that of the fulcrum pivot or trunnion t , immediately below it, as will be seen more particularly by reference to Fig. 5, so that there can be no buckling strain on the connection rod b^8 , or other parts no matter what the positions assumed.

The hand lever b^5 , is fulcrumed loosely on the crank shaft c , which is mounted upon and between bearing brackets h^2 , h^2 , on one end wall h , of one of the holds H . To the outer end of this shaft c , is rigidly secured the hand crank c' , and adjacent thereto is pivotally mounted, as at h^x , on a bracket h^3 , rigidly secured to the outer side of the end wall h , a seat S , for the accommodation of an operator,—said seat being rigidly attached to a sleeve s , (see Fig. 4) fitting on the pivotal support h^x , and being provided with a pendent counterweight s' , by which the seat is maintained in an upright position irrespective of the position of the hold H , or other parts.

The bottom and longitudinal side wall of each hold H , H' , is formed with a watertight float compartment or compartments h^4 , h^4 , which, when the scow is afloat, tend constantly, by reason of the external water pressure, to quarter turn the holds H , H' , upon their pivotal supports t , t' , at right angles to their normal positions as indicated in Fig. 3. Thus when the lower portions of the holds H , H' , are released from the keelson partition K , by the withdrawal of the lower ends of the bolt rods b , b , from the I brackets h' , h' , the holds H , H' , automatically and bodily open up in such manner as to deprive their contents of all support, so that the loads are completely and positively discharged from the holds.

To facilitate the discharge of material the bottoms of the holds H , H' , are preferably inclined or beveled inward toward the keelson partition K , so that the discharge opening is of the maximum width attainable, as will be readily understood by reference to the aforesaid Fig. 3.

After the dumping operation the holds are returned to their normal positions against the keelson partition K , by retractile mechanism of any desired or suitable character. In the drawings I show this accomplished by means of wire ropes or equivalent flexible connections r , r' , windable upon drums

d , d , and having their outer extremities attached to studs h^4 , h^4 , protuberant from the lower portions of the end walls h , of each hold H , H' . Preferably this retractile means is duplicated at each end of the keelson partition, the drums d , d , being secured rigidly to a sleeve shaft d' , mounted upon the rock shaft b^4 , as will be understood by reference more particularly to Figs. 1, 4 and 7, by which it will be seen that additional 75 bearings k^x , are provided on the top of the keelson partition K , for the support of both the sleeve shaft d' , and the rock shaft b^4 —the latter extending to and beyond the bearings k^x , k^x , at either extremity of the keelson partition K , and sufficiently beyond said bearings k^x , k^x , to effect the bolt crank connections heretofore described, while the sleeve shaft d' , is between said bearings k^x , k^x , and not supported thereby, being supported by the rock shaft b^4 , and by said intermediate keelson bearings $k^{x'}$, $k^{x'}$.

The flexible connections r , r' , for each drum d , are of course secured thereto, and wind thereon or unwind therefrom in parallelism upon the same side thereof, one of the strands r' , being passed over an idler roller k^2 , mounted in the top of the keelson partition K , immediately under each drum d , for this purpose, so that the two strands 95 r , r' , extend down one on either side of said keelson partition to and around idler pulleys k^3 , k^3 , mounted in the lower portion thereof, thereby reversing the direction of said strands, one of which r' , is attached to 100 the hold H , while the other r , is attached to the other hold H' . Thus it is obvious that the drums d , d , will either play out the flexible connections to each hold H , H' , simultaneously in opposite directions as the holds 105 rise when released from the keelson partition, as aforesaid, or will simultaneously rewind the connections r , r' , and draw said holds H , H' , back into normal position after said dumping operation, according to the 110 direction of rotation imparted to said drums. The drums d , d , and their sleeve shaft d' , being free to rotate on the withdrawal of the bolts b , b , from the eye brackets h' , h' , the flexible connections r , r' , will 115 automatically adapt themselves to the movements of the holds H , H' , in turning upon their trunnions t , t .

The re-wind of the strands r , r' , upon the drums d , d , is effected by means of crank 120 c' , on the shaft c , to which the small sprocket wheel c^2 , is secured, said sprocket wheel c^2 , being connected by means of the sprocket chain c^3 , with a larger sprocket wheel a' , rigid upon a sleeve a , (see Fig. 10) 125 which is loosely mounted upon a fixed stud t^2 , in axial alinement with the trunnion t , said rotatable sleeve a , having also rigidly secured to it a smaller sprocket wheel a^2 , connected by a sprocket chain a^3 , with a 130

larger gear d^2 , rigidly secured to the sleeve shaft d^7 , upon which the drums are also rigidly mounted. By this or a similar arrangement of differential gearing a relatively small amount of power applied by means of the crank c' , or equivalent, will be amply sufficient to draw the holds H, H' , into normal position against the keelson partition K . A pawl p , on a stationary part may be arranged to act in conjunction with a ratchet wheel c^8 , on the shaft c , to hold the said shaft against retractile movement during the re-wind of the flexible connections r, r' , as indicated in Fig. 9,—said pawl being thrown out of engagement prior to the release of the bolts b, b , for the automatic dumping operation.

h^x, h^x , are reinforcing stay rods or braces rigidly attached to the inner longitudinal side walls of the holds H, H' , and pivotally connected with the keelson partition K , in axial alinement with the trunnions t, t' ; and h^6, h^6 , are dowel studs on the holds H, H' , adapted to fit into coinciding sockets k^4, k^4 , in the keelson partition when the holds are in normal position with relation thereto.

What I claim as my invention and desire to secure by Letters Patent is,

1. A duplex dumping scow of the character designated, comprising twin holds pivotally connected to the upper part of a common keelson partition and detachably secured to the lower part thereof, and said keelson partition, together with means for positioning said holds against said keelson partition, for the purpose described.

2. A duplex dumping scow of the character designated, comprising twin holds formed with float compartments and pivotally connected to the upper part of a common keelson partition and detachably secured to the lower part thereof, said keelson partition, means for releasing the lower parts of said holds therefrom, and means for retracting said holds into normal position against said keelson partition, for the purpose described.

3. In a duplex dumping scow of the character designated, in combination, twin holds formed with float compartments and pivotally connected to the upper part of a common keelson partition and detachably secured to the lower part thereof, said keelson partition, a rock shaft mounted thereon, and bolts actuated by means of said rock shaft, for the purpose described.

4. In a duplex dumping scow of the character designated, in combination, twin holds formed with float compartments and pivotally connected to the upper part of a common keelson partition and detachably secured to the lower part thereof, said keelson partition, a rock shaft mounted thereon, bolts actuated by means of said rock shaft, a sleeve shaft mounted on said rock shaft,

a drum secured to said sleeve shaft, flexible strands connecting said drum with said holds, and means for rotating said sleeve shaft, for the purpose set forth.

5. In a duplex dumping scow of the character designated, in combination, twin holds formed with float compartments and pivotally connected to the upper part of a common keelson partition and detachably secured to the lower part thereof, said keelson partition, a rock shaft mounted thereon, bolts actuated by means of said rock shaft, a sleeve shaft mounted upon said rock shaft, drums secured to said sleeve shaft, flexible strands connecting said drums with said holds, and means for rotating said sleeve shaft, for the purpose described.

6. In a duplex dumping scow of the character designated, in combination, twin holds formed with float compartments and pivotally connected to the upper part of a common keelson partition and detachably secured to the lower part thereof, said keelson partition, a rock shaft mounted thereon, bolts actuated by said rock shaft, means for rocking said shaft manually, and a pivotally supported and counterweighted seat adjacent to said rocking means, for the purpose described.

7. In a duplex dumping scow of the character designated, in combination, twin holds formed with float compartments and pivotally connected to the upper part of a common keelson partition and detachably secured to the lower part thereof, said keelson partition, a rock shaft mounted thereon, bolts actuated by said rock shaft, means for rocking said shaft manually, a sleeve shaft mounted on said rock shaft, drums secured to said sleeve shaft, flexible strands connecting said drums with said holds, means for rotating said sleeve shaft manually, and a pivotally supported and counterweighted seat adjacent to said manually rocking and rotating means, for the purpose described.

8. In a duplex dumping scow of the character designated, in combination, twin holds formed with float compartments and pivotally connected to the upper part of a common keelson partition and detachably secured to the lower part thereof, said keelson partition, a rotatable shaft mounted thereon, a drum secured to said shaft, flexible strands connecting said drum with said holds, and means for rotating said shaft, for the purpose described.

9. In a duplex dumping scow of the character designated, in combination, twin holds formed with float compartments and pivotally connected to the upper part of a common keelson partition and detachably secured to the lower part thereof, said keelson partition, a rotatable shaft mounted thereon, drums secured to said shaft, flexible strands connecting said drums with said

holds, and means for rotating said drum shaft, for the purpose set forth.

10. In a duplex dumping scow of the character designated, in combination, twin holds formed with float compartments and pivotally connected to the upper part of a common keelson partition and detachably secured to the lower part thereof, said keelson partition, a rotatable shaft mounted thereon, drums secured to said shaft, flexible strands connecting said drums with said holds, and means for rotating said drum shaft manually, for the purpose set forth.
11. In a duplex dumping scow of the character designated, in combination, twin holds formed with float compartments and pivotally connected to the upper part of a common keelson partition and detachably secured to the lower part thereof, said keelson partition, a rotatable shaft mounted thereon, drums secured to said shaft, flexible strands connecting said drum with said

holds, means for rotating said drum shaft manually, and a pawl and ratchet detent arranged to prevent retractile movement 25 during such manual rotation, for the purpose described.

12. In a duplex dumping scow of the character designated, in combination, twin holds formed with float compartments and pivotally connected to the upper part of a common keelson partition and detachably secured to the lower part thereof, said keelson partition, a rotatable shaft mounted thereon, drums secured to said shaft, flexible 30 strands connecting said drum with said holds, differential gearing for effecting the rotating of said drum shaft, and means for actuating said differential gearing manually, for the purpose described.

HERMAN W. STORK.
